UNITED STATES PATENT OFFICE

GEORGE P. JACKSON, OF FLUSHING, NEW YORK, ASSIGNOR TO INTERNATIONAL COMBUSTION ENGINEERING CORPORATION, OF NEW YORK, N. Y., A CORPORATION OF DELAWARE.

STEAM GENERATING INSTALLATION

Application filed June 4, 1929. Serial No. 368,227.

This invention relates to steam generating installations and has for its primary object the provision of an improved installation which is inexpensive, compact and effective and which has among its advantages the following.

The obtaining of any desired temperature for superheat through the provision of an arrangement of boiler tubes in advance of the superheater which may readily be increased or decreased in number and the spacing of which may be readily altered.

Ample superheater space with ready accessibility to the superheater and also arranged to be easily made free from air leaks.

The furnace tubes may be of a spacing to meet any type of firing condition and the spacing thereof is not dependent on the spacing of the boiler tubes.

It is another object of the invention to provide—in an arrangement whereby the evaporating elements of the boiler largely define the combustion space of the boiler—an upright two drum boiler unit; front tubes of which in part define a portion of a wall of the combustion space and in part the top of the combustion space, which also afford a space for a superheater, other tubes of such boiler unit serving as convection surface to suitably lower the temperature of gases for entrance into a combustion air heater.

The purpose of this arrangement is to provide a design of installation suitable for average pressures in contradistinction to real high pressures, and it is especially useful in a steam generating installation adapted to be operated at high ratings with high capacity.

It is still another object of the invention to provide a two drum upright boiler unit in combination with other evaporating surfaces defining combustion space of the installation in such manner that substantially all of the active heat absorbing surface of the installation discharges steam above the water line while, at the same time, adequate supply for all of such active heat absorbing surface is ensured.

How the foregoing, together with such other objects and advantages as may herein-after appear, or are incident to my invention,

are realized is illustrated in preferred form in the accompanying drawings, wherein—

Fig. 1 is a vertical section through an installation embodying my invention, and

Fig. 2 is a fragmentary cross section taken on the line 2—2 of Fig. 1.

My improved steam generating installation comprises in general a combustion chamber A which is largely defined by tubes subject to radiant heat, as will hereinafter fully appear; a boiler unit B of novel construction associated with the combustion chamber, the combustion chamber being located in front of and beneath the boiler unit; a superheater C located in a superheater space D provided in the boiler unit B, burner means E for admitting finely divided fuel and air into the combustion chamber in a manner to produce turbulent and intense combustion, the burners being preferably tangentially disposed; an offtake F for the products of combustion; and an air heater G located in the offtake.

The boiler unit B comprises a lower mud drum 3, an upper steam and water drum 4, a bank of upright convection tubes 5 connecting said drums, upper front header means, in this instance comprising a row of upper front headers 6 located to one side of the drum 4 and spaced substantially therefrom, although it is to be understood that a single box header may be employed, a bank of bent boiler tubes 7 connecting the lower drum 3 and the headers 6, a plurality of upcomer tubes 8 leading from the headers 6 to the steam space of the upper drum 4, suitable baffling 9 in the bank of tubes 7 arranged to provide a top outlet 10 for the combustion chamber communicating with the superheater space D and suitable baffling 11 for the bank of tubes 5 arranged to provide a plurality of up and down passes for the gases of combustion in their passage from the superheater space D to the offtake F.

The tubes of the bank 7 are arranged in vertical spaced rows and as herein shown each row consists of five tubes. These tubes extend vertically upward from the drum 3 for a portion of their length and then bend and extend substantially horizontally for the re-

100

mainder of their length, it being preferable to have them incline slightly toward the headers. The vertical portion of this bank of tubes is located closely adjacent the upright 5 bank of convection tubes 5.

Through the arrangement of boiler just described I am enabled to provide ample space between the substantially horizontally extending portion of the bank of tubes 7 and 10 the upcomer tubes 8 for the location of the superheater C. A superheater so located is readily accessible for repairs and cleaning. The upcomer tubes 8 constitute the top of 15 the superheater space and act as a support for a sheathing or covering for the space. Thus I have provided an inexpensive construction which can easily be made free from air leaks.

The arrangement of tubes below the superheater can be made so as to give any desired 20 temperature at the superheater both in regard to any spacing that is desirable in these tubes and also as to the number of tubes desired in a vertical direction. If it is desired 25 to obtain lower superheat temperature, a greater number of tubes may be employed in the bank 7. Also, if it is desired to increase the superheat temperature certain of the tubes may be removed, in which case the idle 30 tube holes in the headers would be plugged. The arrangement of the tubes of the bank 7 is such that definite circulation is provided, it being noted that a very substantial individual head is provided in these tubes.

35 The combustion chamber A above referred to has its front wall defined by a row of closely spaced upright tubes 12 which pass outwardly to the exterior of the combustion chamber at their lower and upper ends for 40 connection into the outside lower and upper headers 13 and 14 respectively. A plurality of upcomer tubes 15 lead from the upper headers 14 of the front wall tubes to the steam space of the drum 4. The tubes 15 pass inwardly from the headers 14, then upwardly 45 through the spaces between the vertical rows of tubes of the bank 7 and then bend and pass rearwardly along the upper part of the superheater space D to the steam space of the drum 50 4. It will be noted that the tubes 12 of the front wall pass outwardly at their upper ends at a point below the horizontally extending 55 portions of the tubes of the bank 7, and, therefore, the spacing of these tubes is not dependent on the spacing of the tubes in the bank 7 and consequently any spacing can be used in the front wall to suit operating conditions. In the drawings I have shown the spacing of the tubes 12 considerably less than 60 the spacing of the rows of tubes of the bank 7.

The bottom of the combustion space is defined by a row of tubes 16, which tubes incline upwardly and forwardly from the lower rear header or small drum 17 to the lower 65 header 13 of the front wall. A plurality of

downcomers 18 are connected at their upper ends into the drum 3 and at their lower ends into the header 17 to supply water to the header 17 from the drum.

The lower rear portion of the combustion chamber is defined by a row of upright tubes 19 which are connected at their lower ends into the lower header 17. The tubes of this row at their upper ends are connected to elbows 20 located inside the drum 3, which elbows serve to connect the tubes 19 with a row of upright tubes 21 grouped with the tubes of the convection bank 5 and extending upwardly for connection into the steam space of the upper drum 4.

80 Each side of the combustion space is defined by a row of closely spaced upright tubes 22, the lower ends of which are connected into an outside header 23 and the upper ends of which are connected into an outside header 24. The headers 23 are supplied from the small drum 17 by a plurality of bent tubes 25 and the upper headers 24 deliver to the upper drum 4 by means of a plurality of upcomer tubes 26 connecting the upper headers with the steam space of the drum 4. The tubes of the rows 12, 19 and 22 are preferably provided with longitudinally extending fins.

85 The upper rear portion of the combustion chamber is defined by the vertically extending portion of the bank of tubes 7 and the top of the combustion chamber is formed by the substantially horizontally extending portion 90 of the bank of tubes 7. Stated in another way I have provided an upright two drum boiler 95 unit having tubes so arranged that front tubes thereof in part define a portion of a wall of the combustion space of the installation and in part the top of the combustion space.

100 In an installation of the character described the tubes of the bank 5, under most operating conditions, act as downcomers and, therefore, adequate supply for all of the active heat absorbing surface is ensured, not only because of the head but also because of the pull caused by the active heat absorbing surfaces, all of which discharge above the water line and receive their supply from the lower drum. Inasmuch as all of the active heat absorbing 105 surfaces discharge steam above the water line of the upper drum a high quality of steam is ensured. The pull of the bank of tubes 5 also makes for a high quality of steam. To further ensure that a high quality of steam is obtained, I may employ baffling in the drum 110 4, such, for example, as a perforated plate.

115 The arrangement of the tubes of the bank 5 may be made to give, within reasonable limits, any desired gas temperature at the exit dependent on the size of drum employed and the baffling arrangement.

120 I claim:—

1. A boiler comprising, in combination, an upper steam and water drum, a lower mud drum, vertically extending bent tubes con- 125

- necting said drums, upper header means located to one side of the upper drum, a bank of tubes connecting the lower drum to said header means comprising a plurality of rows 70
 6 of bent tubes, said tubes extending vertically adjacent to the aforesaid vertically extending bent tubes for a portion of their length and substantially horizontally for the remainder of their length, tubes connecting said upper
 10 header means with the steam space of the upper drum, said last mentioned tubes and the substantially horizontal portion of said bank of tubes constituting the upper and lower boundaries of a superheater space, and a superheater located in said space. 75
 15
2. A boiler comprising, in combination, an upper steam and water drum, a lower mud drum, upper header means located to one side of and substantially spaced from the upper drum, a bank of vertical, bent tubes connecting said drums, a bank of bent tubes connecting the mud drum and the upper header means, the tubes of said bank extending vertically adjacent to the first mentioned bank of tubes for a portion of their length and substantially horizontally in the upper portion of the boiler for the remainder of their length, a row of tubes connecting the upper header means to the steam space of the upper drum, said row of tubes being spaced above the substantially horizontal portion of the second bank to provide a superheater space therebetween, and a superheater located in said space. 80
 20

- connecting said drums, a bank of bent tubes connecting the mud drum to the set of upper headers, said tubes being arranged in spaced vertical rows and extending vertically for a portion of their length and substantially horizontally for the remainder of their length, and tubes connecting said set of headers with the steam space of the upper drum; a combustion chamber located in front of and beneath said boiler; boiler tubes in the combustion chamber and marginal of combustion space thereof including a row of vertical tubes lining the front wall of the combustion chamber, a header into which the lower ends of said tubes are connected, a header into which the upper ends of said tubes are connected, means for connecting the lower header to the mud drum of the boiler, and tubes connecting the upper header into the steam space of the upper drum of the boiler, said tubes extending upwardly through the spaces between the rows of tubes of the bank connecting the mud drum to the upper set of headers of the boiler and then rearwardly to the upper drum; and means for introducing fuel into the combustion chamber to be burned in space therein.
5. In combination, an upper and a lower drum, a bank of upright convection tubes connecting them, a set of upper headers to one side of and spaced from the upper drum, a bank of bent boiler tubes connecting the lower drum to said set of headers, the tubes of said bank being arranged in vertical spaced rows and extending upright for a portion of their length and substantially horizontally for the remainder of their length, the upright portion thereof being adjacent the upright convection bank, tubes connecting said set of headers to the steam space of the upper drum, a combustion chamber the top of the combustion space of which is defined by the substantially horizontal portion of the bank connecting the lower drum and the set of headers and an upright portion of which is defined by the upright portion of said bank, a superheater space above said substantially horizontal portion of said bank, a superheater in said space, baffling for said last mentioned bank providing an outlet from the combustion chamber to the superheater space, and baffling for said bank of convection tubes providing up and down gas passes in said bank, an offtake, an air heater in said offtake, and means for introducing fuel into the combustion chamber to be burned in space therein.
6. In combination, an upper and a lower drum, a bank of upright convection tubes connecting them, a set of upper headers to one side of and spaced from the upper drum, a bank of bent boiler tubes connecting the lower drum to said set of headers, the tubes of said bank being arranged in vertical spaced rows and extending upright for a

- portion of their length and substantially horizontally for the remainder of their length, the upright portion thereof being adjacent the upright convection bank, tubes connecting said set of headers to the steam space of the upper drum, a combustion chamber the top of the combustion space of which is defined by the substantially horizontal portion of the bank connecting the lower drum 5 and the set of headers and an upright portion of which is defined by the upright portion of said bank, radiant heat tubes largely defining the remainder of the combustion space, downcomer connections from the lower drum to the radiant heat tubes and upcomer connections from the radiant heat tubes to the steam space of the upper drum, a superheater space above said substantially horizontal portion of said bank, a superheater 10 in said space, baffling providing an outlet from the combustion chamber to said superheater space, an offtake, and other baffling associated with the first baffling to provide up and down passes among the convection bank for the gases of combustion in their passage from the superheater space to the offtake, an air heater in said offtake, and means for introducing fuel into the combustion chamber to be burned in space therein. 15
7. In combination, a boiler including upper and lower rear drums, a bank of upright convection tubes connecting said drums, a row of upper front headers, a bank of bent tubes connecting the lower drum and said 20 headers, the tubes of said bank extending upright for a portion of the length and substantially horizontally for the remainder of their length and being arranged in vertical spaced rows, tubes connecting said headers to the steam space of the upper drum, a combustion chamber located in front of and beneath the boiler, a row of upright radiant heat tubes defining the front wall of the combustion chamber, means connecting said 25 radiant heat tubes to the lower drum, an upper header into which the upper ends of said tubes are connected, upcomer tubes connecting said upper header into the steam space of said drum, and means for introducing fuel into the combustion chamber to be burned in space therein. 30
8. In combination, a boiler including upper and lower rear drums, a bank of upright convection tubes connecting said drums, a row of upper front headers, a bank of bent tubes connecting the lower drum and said 35 headers, the tubes of said bank extending upright for a portion of the length and substantially horizontally for the remainder of their length and being arranged in vertical spaced rows, tubes connecting said headers to the steam space of the upper drum, a combustion chamber located in front of and beneath the boiler, a row of upright radiant heat tubes defining the front wall of the 40 combustion chamber, means connecting said radiant heat tubes to the lower drum, an upper header into which the upper ends of said tubes are connected, upcomer tubes connecting said upper header into the steam space of said drum, and means for introducing fuel into the combustion chamber to be burned in space therein. 45
